UNITED STATES PATENT OFFICE.

WILLIAM NUNLEY, OF NEWARK, NEW JERSEY.

TOOL-HANDLE.

SPECIFICATION forming part of Letters Patent No. 310,959, dated January 20, 1885.

Application filed June 7, 1884. (No model.)

To all whom it may concern:

Be it known that I, WILLIAM NUNLEY, a citizen of the United States, residing at Newark, in the county of Essex and State of New Jersey, have invented certain new and useful Improvements in Handles; and I do hereby declare the following to be a full, clear, and exact description of the invention, such as will enable others skilled in the art to which it applies to make and use the same, reference being had to the accompanying drawings, and to letters of reference marked thereon, which form a part of this specification.

The object of this invention is to provide an improved handle for leather-shavers' steels and similar small tools requiring light settings, which, while possessing simplicity and cheapness of construction and the requisite lightness, will allow a ready withdrawal of the shank should the tool be broken off at the handle.

The invention consists in the peculiar arrangements and combinations of parts, substantially as will be hereinafter set forth, and be finally embodied in the clauses of the claim.

Referring to the accompanying drawings, in which similar letters of reference indicate like parts in each of the several figures, Figure 1 is an elevation of the tool; Fig. 2, a longitudinal section of the same; Fig. 3, an elevation of a certain core-piece, and Fig. 4 a section thereof.

In said drawings, A is the wooden body of the handle, which is perforated and recessed at a point near the tool, the perforation (marked a) being in a transverse position as related to the recess b.

B is a metallic core-piece fitting tightly into the recess in the handle, and provided with a perforation, a', corresponding to that in the handle, and having a slightly-tapering shank-socket, c, adapted to receive the shank of the tool and hold the same without extra fastenings.

C is the tool, which in the case shown is a leather-shaver's steel having a tapering shank, c', corresponding to the socket c, and fitting so tightly in said socket as to require considerable force—more than the mere weight of the tool or any force derived from impact occasioned during ordinary usage—to disconnect the parts. Said shank extends suffi-

ciently back into the perforation a', as in Fig. 1, to enable a pin or bar to have sufficient play to throw the same from holding contact. 55

Heretofore shavers' steels have been ordinarily secured in a simple wooden handle, similar in contour to the one shown. If by accident the steel were broken, it was practically impossible to withdraw the shank, so that it became necessary to get an entirely new outfit at a consequent waste of time and money.

By means of the improved device, should the tool be broken at or near the handle, I 65 may remove the shank by inserting a pin or bar of any suitable size through the perforations a a', thus obtaining a leverage, and then by pressing against the projecting end of the shank the latter is easily thrown from holding contact. 70

The handle may be used to advantage in connection with jewelers' or other light tools.

I am aware that it is not new to provide wooden handles with metallic core-pieces to 75 receive the tool, and that in some cases these core-pieces have, with the wooden handle, been transversely perforated; but where the perforations have been formed they have been to receive a permanent pin or rivet to hold the 80 core to the wooden handle, and have not allowed the insertion of a lever to force out the shank, as in the case above described.

I am also aware that in heavy tools—such, for example, as millstone-picks and other 85 stone-working tools—the shank of a tool has been secured in an all-metal head or handle having a transverse opening, to enable a wedge to be driven against the end of said shank to force the tool out of the handle or head; but 90 such a construction, even if brought down to a proper size, would be practically worthless because of its excessive weight. It will thus be understood that I do not claim, broadly, a core-piece secured to its handle by a pin running through both of them, or anything involved in such a construction, nor, broadly, a head or handle having a transverse perforation enabling the tool to be forced from its seat; 95

What I claim as my invention is—

The improved handle for leather-shavers' steels, consisting of a recessed and perforated handle-body, A, and a recessed and perforated

metallic core-piece, B, arranged in the recess of the said body, the perforations in said body and core-piece corresponding to make a continuous transverse perforation, and the recess in the said core-piece extending to the transverse perforation therein to allow the shank to project into said perforation, substantially as and for the purposes set forth and shown.

In testimony that I claim the foregoing I have hereunto set my hand this 23d day of 10 May, 1884.

WILLIAM NUNLEY.

Witnesses:
